Primary Examiner — Cathron C Brooks*Assistant Examiner* — Andrew T Nemeth(74) *Attorney, Agent, or Firm* — Oblon, McClelland, Maier & Neustadt, L.L.P.(57) **CLAIM**

The ornamental design for a display screen or portion thereof with graphical user interface, as shown and described.

DESCRIPTION

FIG. 1 is a front elevational view of a display screen or portion thereof with graphical user interface; and, FIG. 2 is another front elevational view thereof, but shown without the broken line showing of portions of the graphical user interface.

The outermost broken lines in FIGS. 1 and 2 show a display screen or portion thereof, and form no part of the claimed design. The other broken lines in FIG. 1 show portions of the graphical user interface that form no part of the claimed design.
